UNITED STATES PATENT OFFICE.

WILLIAM WILLIAMS, OF CALEDONIA, OHIO, ASSIGNOR OF ONE-HALF TO
RUSSELL W. ROBERTS AND CHARLES F. OBETZ, OF SAME PLACE.

THILL-COUPING.

SPECIFICATION forming part of Letters Patent No. 283,309, dated August 14, 1883.

Application filed February 24, 1883. (No model.)

To all whom it may concern:

Be it known that I, WILLIAM WILLIAMS, a citizen of the United States, residing at Caledonia, in the county of Marion and State of Ohio, have invented certain new and useful Improvements in Thill-Couplings; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to improvements in thill-couplings; and it consists in the construction, combination, and arrangement of the several parts, as will be hereinafter fully described, and specifically pointed out in the claims.

In the drawings, Figure 1 is a side view of my improved coupling. Fig. 2 is a vertical longitudinal section of the same. Fig. 3 is a side view of the thill-hook and cylinder. Fig. 4 is a top view of the thill-iron and rubber block. Fig. 5 shows a perspective and a cross-sectional view of the cylinder, and Fig. 6 is a detail perspective view of the rubber-block.

a is the thill-hook, secured on the forward end of the clip-plate, which is made fast to the fore axle in suitable manner. When so desired, the hook could be formed on or made fast directly to one of the arms of the axle-clip. This hook is provided on its upper side with the escape-opening *a'*, and its forward side is made thinnest at a point, *a''*, in line with the draft, and it is thickened at *a''' a'''*, respectively, above and below the point *a''*, in line of draft, as shown in Figs. 1, 2, and 3, and for the purposes hereinafter described.

b is a screw turning through the under side of the hook *a*, nearly diametrically opposite the escape-opening *a'*, as shown. This screw is made sufficiently long so that its point may extend through the hook when it is turned in through the same.

c is a cylinder made of a size to fit snugly within the hook *a*, and adapted to be placed and revolved in the said hook. It is provided with a seat, *c'*, corresponding to the escape-opening *a'*, and adapted to receive the cross-bar of the thill-iron, as will be described.

c'' is a groove cut in the cylinder *c* in a plane parallel to the line of draft, and made deepest at a point diametrically, or nearly so, opposite the seat *c'*, as shown in Fig. 5. This groove continues entirely to the seat *c'* on what, for convenience of reference, I call the "upper side" of the cylinder, while on its lower side it extends only to a point, *c''*, at about right angles to the seat *c'*, where it runs out to the periphery of the cylinder, as shown in Figs. 2 and 5. The point of the screw *b* extends into the groove *c''*, and it will be seen that the cylinder cannot be turned from left to right beyond the point at which it is shown in Fig. 2, but that it can be turned in the opposite direction until the seat *c'* comes over the point of the screw, and the cylinder may be removed endwise out of the hook when the screw or the thill-iron has been removed. I prefer, however, to use the screw, as thereby all wear in the groove may be compensated for by increasing the length of the projection in the hook.

d is the thill-iron, having the cross-bar *d'*, adapted to be passed through the opening *a'* and to rest in the seat *c'*, as shown, and having the opening *d''*, which slips over the point of the hook, and is made sufficiently large to receive the rubber block *e*, as shown.

In the operation of the device the cylinder *c* is turned to bring the seat *c'* under the opening *a'*, and the cross-bar *d'* is passed down into the seat *c'*, and the thill is turned down to the position shown in Figs. 1 and 2; and the rubber block *e* bears between the front of the hook and the forward wall of the opening and prevents all rattling. By making the hook thicker above and below the line of draft or normal position of the thill, the latter is prevented in the first instance from being thrown up by any ordinary motion, and is held up from the ground by the portion thickened below the line of draft. It is aided in the latter operation by the groove *c''* on the cylinder *c*, terminating on what I have called the "under side" of the cylinder at a point about at right angles to the seat *c'*, as has been described.

It might in some cases be desirable to use metallic coil or bar springs instead of the rubber block *e*; but I prefer to use the latter, as it is convenient and easy of application.

Instead of extending the groove c^2 up to the seat c' , as has been described, it might be made to terminate on what I have denominated the "upper side" at a point diametrically opposite the point c' , so that the cylinder could be taken out and reversed when one end of the groove had been considerably worn by the bearing of the point of screw b , or a projection used in lieu thereof. I prefer, however, the 10 construction shown and before described.

Having thus described my invention, what I claim, and desire to secure by Letters Patent, is—

1. In a thill-coupling, the hook a , provided 15 with the enlarged parts $a^3 a^4$ and the intervening thin part, a^2 , in combination with the cyl-

inder c and thill-iron d , provided with cross bar d' , substantially as described, and for the purposes set forth.

2. In a thill-coupling, the hook a , provided 20 with the enlarged parts $a^3 a^4$ and the intervening thin part, a^2 , in combination with the cylinder c , thill-iron d , having opening d^2 , and the rubber block e , substantially as described, and for the purposes set forth.

25 In testimony whereof I affix my signature in presence of two witnesses.

WILLIAM WILLIAMS.
